United States Patent Office

Des. 185,476
Patented June 9, 1959

185,476

DRAWER PULL

Paul Westman, Lakewood, N.Y., assignor to Weber-Knapp Company, Jamestown, N.Y., a corporation of New York

Application March 26, 1958, Serial No. 50,193

Term of patent 7 years

(Cl. D10—8)

Fig. 1 is a perspective view of a drawer pull showing my new design; and

Fig. 2 is a side elevational view thereof.

I claim:

The ornamental design for a drawer pull, substantially as shown.
